A. S. Gattison
Attorney

UNITED STATES PATENT OFFICE.

HARVEY O. BEMISDERFER, OF HAMMOND, INDIANA, ASSIGNOR TO CENTRAL RAILWAY SIGNAL COMPANY, OF PITTSBURGH, PENNSYLVANIA, A CORPORATION OF NEW JERSEY.

RAILWAY SIGNAL TORPEDO.

Application filed November 14, 1921. Serial No. 514,988.

To all whom it may concern:

Be it known that I, HARVEY O. BEMISDERFER, a citizen of the United States, residing at Hammond, in the county of Lake and 5 State of Indiana, have invented certain new and useful Improvements in Railway Signal Torpedoes, of which the following is a specification, reference being had therein to the accompanying drawing.

10 This invention relates to improvements in railway signal torpedoes, comprising, an explosive, a container therefor and a rail engaging member for attaching the torpedo to the rail head of a railroad track. In designing and manufacturing a railway signal torpedo there are certain characteristics which must be incorporated in the torpedo. Among the more important characteristics which must be incorporated in the completed torpedo is a water tight container for the explosive. In addition to the water tight container the torpedo must be provided with a rail engaging member which is secured firmly to the torpedo and which 25 must be capable of fastening the torpedo sufficiently secure to the rail head of a railroad track so that it will not be displaced when it is struck by the moving wheel of a railroad engine, car, or the like.

30 In addition to these attributes the container, rail engaging member, and the method or manner of fastening the rail engaging member to the container must be simple and cheap of manufacture to make 35 the device capable of being marketed at a saleable competitive price.

Having in mind these necessary attributes of an efficient railway signal torpedo, I have invented a torpedo which is an improvement over anything now known and 40 which is hereinafter more particularly described.

The object of my invention is to provide a torpedo of the railway explosive type, 45 which is provided with a container comprising several folds of preferably fibrous material, wherein the last or outer fold is secured in a new and novel manner.

Another object of my invention is to provide 50 a novel railway signal torpedo of the explosive type which is provided with a pliable rail engaging member.

Other and further objects and improved

results of my novel railway signal torpedo construction will appear in the following description and accompanying drawings.

In the drawings:—

Fig. 1 is a perspective view of a railway signal torpedo constructed in accordance with my improved invention.

Fig. 2 is a plan view showing the fibrous blank which composes, when folded, the container for the explosive, a modified form of this blank being shown in dotted lines.

Fig. 3 is a vertical sectional view through my improved torpedo, the section being taken transversely the rail engaging member.

Fig. 4 is a vertical sectional view through my improved torpedo the view being taken longitudinally of the rail engaging member.

Fig. 5 is a bottom plan view of my improved torpedo showing the novel manner of fastening the final fold of the explosive wrapper or container.

Fig. 6 is a bottom plan view of my improved torpedo showing a modified form of fastening the final fold of the explosive wrapper or container.

Referring now to the drawings in which like parts are designated by similar reference numerals throughout the invention, A designates a fibrous blank and as shown in Fig. 2 the blank is in its extended position preparatory to receiving the explosive 1, 85 which is preferably of tablet form, and of a shape and size to fit within the depressed portion 2 of the central area or portion 3 of the container A.

The blank or container A consists in addition to the central area or portion 3 and the depressed portion 2 of the four wings 5, 6, 7 and 8.

The portions 5 and 7 of the blank which are opposite to one another are of an approximate rectangular shape and in assembling my torpedo these portions are folded inwardly upon the explosive which has previously been placed in the depressed portion 2 of the container blank. The ends 100 of the portions 5 and 7 abut as appears at 30 and a water proofing cement 9 completely covers their outer faces. The portions 6 and 8 of the container blank are opposite one another and the portion 6 is of an approximate square shape and contains openings

10 through which is threaded the rail engaging member 11, as clearly appears in the drawings.

The next step in assembling my torpedo 5 is to fold the portions 6 inwardly upon the cemented surfaces of the portions 5 and 7 which it will completely cover.

The final step to produce my completed torpedo is to apply cement to the inner face 10 of the portion 8 of the container case and fold the same inwardly upon the previously inwardly folded portion 6. As clearly appears in the drawings the portion 8 has inwardly slanting sides 9 which meet in a flat 15 end 13 which is of a length equal to about one half the distance between the openings 10 in the portion 6 of the blank A.

When the portion 8 is bent inwardly its 20 end 13 is inserted beneath the portion 14 of the rail engaging member 11 as clearly appears in Fig. 5 of the drawings. The portion 14 of the rail engaging member is then pulled tightly down upon the end 13 of the 25 fold or portion 8 of the container blank and by means of the cement on the under side of this portion, the portion is locked firmly in place making a completely water proof container for the torpedo explosive.

The elements which go to make up the 30 modified form of my torpedo as shown in Fig. 6 of the drawings are identical to those described as composing the preferred form with the exception that the portion 8 of the preferred form is replaced by the portion 8' 35 which is of a considerably different shape. The portion 8' has its sides 9' slanting inwardly from a point about midway the length of the portion and for a distance about two-thirds of the width of the portion 40 leaving a tongue 13' which is about one-third the width of the portion 8' and approximately one-third its length.

When the portion 8' is bent inwardly upon the torpedo case the tongue 13' is inserted 45 beneath the portion 14 of the rail engaging member in a similar manner as the end 13 in the preferred form.

The rail engaging member disclosed in the drawings is what is known in the art as 50 a lead strap. This strap is very pliable and when fastening the torpedo to the rail head the strap is bent around the rail head to hold the torpedo in place.

From the foregoing it will be seen that I 55 have provided a railway signal torpedo of the explosive type which is practically free from the objection heretofore known in torpedoes; namely that of flying particles of metal when the torpedo is exploded.

In addition to the above advantage it will 60 be readily seen that my torpedo is simple and cheap of manufacture inasmuch as the torpedo can be assembled very rapidly and the completed structure comprises a very 65 limited number of parts.

I also wish it to be understood that I do not limit myself to the particular shape of the portions 8 or 8' of the torpedo container as it will be readily understood that these portions could be made in shapes different 70 from those shown in the drawings without departing from the spirit of my invention.

I claim—

1. A railway signal torpedo comprising, 75 an explosive, a casing for the explosive comprising several folds of material, a rail engaging member carried by the torpedo, and the final outer fold of the container locked beneath the rail engaging member.

2. A railway signal torpedo comprising 80 an explosive, a casing for the explosive composed of a plurality of folds of material, one of the folds provided with openings through which a rail engaging member is threaded, and the final fold of the explosive casing locked beneath the rail engaging member intermediate the openings through which said rail-engaging member is threaded.

3. A railway signal torpedo comprising 85 an explosive, a casing for the explosive composed of several folds of material, one of the folds of the container provided with openings through which is threaded a rail 90 engaging member, and the final fold of the casing having its end reduced whereby it can be inserted beneath the rail engaging member intermediate the openings through which said rail-engaging member is threaded, for the purpose described.

4. A railway signal torpedo comprising 95 an explosive, a case for the explosive composed of several folds of material, a rail engaging member threaded through openings in the case, the ends of the rail 100 engaging member extending outwardly from beneath the folds of the case and the final fold of the case locked beneath the rail engaging member.

5. A railway signal torpedo comprising 110 an explosive, a case for the explosive composed of several folds of material, a rail engaging member threaded through openings in the case, and the final fold of the 115 torpedo having its end reduced as to width, whereby it may be inserted beneath the rail engaging member intermediate the openings in the case.

6. A railway signal torpedo comprising 120 an explosive, a case for the explosive composed of several folds of material, a rail engaging member threaded through openings in the case, and a portion of the final fold of the case of a width substantially equal to the distance between the 125 openings in the case, whereby the end of the final fold of the case can be inserted beneath the rail engaging member intermediate the case openings for locking said final fold in closed position.

7. A railway signal torpedo comprising an explosive, a casing for the explosive composed of a plurality of folds of material, one of the folds provided with openings 5 through which a rail-engaging member is threaded, and the final outer fold of the explosive casing locked beneath the rail-engaging member.

8. A railway signal torpedo comprising 10 an explosive, a casing for the explosive com-

posed of several folds of material, one of the folds provided with openings through which is threaded a rail-engaging member, and the final fold of the casing having its ends reduced whereby it can be inserted beneath the rail-engaging member. 15

In testimony whereof I hereunto affix my signature.

HARVEY O. BEMIS DERFER.
